TOY TRUCK

Ira B. Gilford, Thousand Oaks, and Alan W. B. Nash,
Torrance, Calif., assignors to Mattel, Inc., Hawthorne,
Calif.

Original design application Mar. 2, 1970, Ser. No.
21,671. Divided and this application Sept. 1, 1971,
Ser. No. 177,214

Term of patent 14 years

Int. Cl. D21—01
U.S. Cl. D34—15 AJ

FIG. 1

FIG. 2

FIG. 3

FIG. 4

FIG. 5

FIG. 1 is a front perspective view of a toy truck showing our new design; and

FIG. 2 is a rear elevational view of FIG. 1; and
FIG. 3 is a left side elevational view of FIG. 1; and
FIG. 4 is a top plan view of FIG. 1; and
FIG. 5 is a bottom plan view.

This application is a division of application Ser. No. 21,671, filed Mar. 2, 1970, and assigned to the assignee of the present invention.

We claim:

The ornamental design for a toy truck, as shown and described.
